UNITED STATES PATENT OFFICE.

AUGUSTIN J. CHEVRETTE, OF WORCESTER, MASSACHUSETTS, ASSIGNOR TO CROMPTON & KNOWLES LOOM WORKS, A CORPORATION OF MASSACHUSETTS.

SHUTTLE-CHANGING LOOM.

Application filed October 31, 1922. Serial No. 598,123.

To all whom it may concern:

Be it known that I, AUGUSTIN J. CHEVRETTE, a citizen of the United States, residing at Worcester, in the county of Worcester and State of Massachusetts, have invented a new and useful Shuttle-Changing Loom, of which the following is a specification.

This invention relates to a shuttle changing loom of the type disclosed in the prior patent to E. H. Ryon, Serial No. 414,046, filed October 1, 1920.

It is the general object of my invention to provide improved mechanism in such a loom by which the ejected shuttle may be transferred to a shuttle storage receptacle. A further object is to provide improved driving connections for such mechanism, whereby the mechanism remains at rest between shuttle transfers and whereby it receives an even continuous movement when placed in operation at the time of transfer.

My invention further relates to arrangements and combinations of parts which will be hereinafter described and more particularly pointed out in the appended claims.

A preferred form of the invention is shown in the drawings in which—

Fig. 1 is an end elevation of a shuttle changing loom embodying my improvements;

Fig. 2 is a detail plan view, looking in the direction of the arrow 2 in Fig. 1;

Figs. 3 and 4 are partial end elevations showing the mechanism in different operating positions;

Fig. 5 is a sectional elevation, taken along the line 5—5 in Fig. 3;

Fig. 6 is a detail sectional plan view, taken along the line 6—6 in Fig. 3; and

Fig. 7 is a detail plan view looking in the direction of the arrow 7 in Fig. 5.

Referring to the drawings, I have shown a loom frame 10 on which is mounted a lay 11 having vertically moving shuttle boxes 12 by which a shuttle change is effected. The boxes 12 are mounted on a lifter rod 13 having a give-way connection 14 at its lower end to a lifter lever 15 mounted on a fixed pivot 16. An actuating lever 17 is also mounted on the fixed pivot 16 and is regularly oscillated by a cam 18 mounted on the usual bottom or cam shaft 19. The actuating lever 17 normally moves independently of the lifter lever 15 but is

provided with a latch 20 by which it may be connected thereto. The latch 20 is controlled by weft detector mechanism not shown.

The parts thus far described form no part of my invention and for a more complete description of these parts and also of the shuttle feeding devices, reference is made to the Ryon application above noted.

When a shuttle change occurs, the exhausted shuttle S is ejected from the upper or regular shuttle box 12 as the latter moves rearward in raised position, the shuttle S being received in a removal box or receptacle 21 which is pivoted at 22 to the end of a lever arm 23 mounted to swing about a fixed pivot 24.

A lifting link 25 is pivoted at its upper end to the lever 23 and is provided with a roll 26 resting upon a cam 27 fixed to a large gear 28 and rotatable upon a shaft or stud 29. The lower end of the link 25 is slotted at 30 to receive the end of the stud 29 by which it is guided in its vertical movement.

The gear 28 meshes with a pinion 31 loosely mounted and slidable on the cam shaft 19 previously described. A clutch disc 32 is secured to the face of the cam 18 fast on the shaft 19 and is provided with one or more notches or recesses 33 (Fig. 7) adapted to receive the end of the stud 29 by which it is guided in its vertical movement.

The pinion 31 has a grooved hub 35 engaged by the forked end of a release lever 36 (Fig. 6). A light spring 37 is connected to the outer end of the lever 36 and acts to yieldingly hold the pinion 31 out of driving engagement with the disc 32. A cam-like lug or projection 38 (Figs. 3 and 6) on the side of the large gear 28 engages an upward projection 39 on the lever 36 and positively disengages the pinion from the clutch disc at the end of a single revolution of the gear 28.

The cam 27 is so located on the gear 28 that the weight of the cam 27, the link 25 and parts associated therewith continues the advance movement of the gear 28 after the pinion 31 is withdrawn, so that the cam lug 38 will pass slightly beyond the projection 39, as indicated in Fig. 1, thus permitting the pinion 31 to be again engaged with the clutch disc 32 by the mechanism about to be described. A recess 27 in the

cam 27 receives the roll 26 and assists in yieldingly maintaining the parts in the normal position shown in Fig. 1.

This mechanism comprises a grooved collar 40 slidable on the end of the cam shaft 19 and adapted to compress a relatively heavy coil spring 41 which is loosely mounted on the shaft 19 and engages the outer face of the pinion 31. The collar 40 receives the forked end of a bell crank 42 mounted on a fixed pivot 43 and having its lower end extended into the path of movement of an arm 44 projecting rearwardly from the shuttle box lifter lever 15 and movable therewith.

The removal box 21 is open at its top and front side and is provided with a cam roll 45 which travels in the curved slot of a fixed cam plate 46 as the lever 23 is raised by rotation of the cam 27 from the position shown in Figs. 1 and 3 to the position shown in Fig. 4. The cam roll 45 co-operates with the cam plate 46 to swing the removal box 21 around its pivot on the lever 23, thus elevating the rear portion of the box and depositing the shuttle S in the fixed shuttle storage receptacle 47.

Having described the details of construction of my improved mechanism, the operation thereof will be readily understood. The normal running position of the parts is shown in Fig. 1. When weft exhaustion is indicated, the latch 20 is moved inward through the opening in the actuating lever 17 and engages the under side of the lever 15, as the lever 17 is raised by the cam 18. Such engagement causes elevation of the shuttle box 12 and the exhausted shuttle S is deposited in the removal box 21 as indicated in Fig. 3.

As the lever 15 moves upward, the arm 44 fixed thereto moves downward, engaging the bell crank 42 as shown in Fig. 5 and compressing the spring 41, thus overcoming the tension of the light spring 37 (Fig. 6) and holding the pinion 31 yieldingly against the clutch disc 32 until the pin 34 can enter the notch or recess 33 in the disc. Driving engagement is thus provided for the pinion 31, which thereafter rotates the large gear 28 and gives the cam 27 a complete operative movement by which the removal box 21 is raised to the position shown in Fig. 4 to transfer its shuttle to the storage receptacle 47. The box 21 is then returned to the normal lower position shown in Fig. 1.

The driving pressure upon the pin 34 in the pinion 31 is sufficient to prevent disengagement of the clutch parts until the rotation of the gear 28 is substantially completed, when the cam lug 38 on the gear 28 engages the projection 39 on the lever 36 and positively disengages the clutch. It will be noted that the gear 28 is much larger than the pinion 31, the shaft 19 thus making

several revolutions during a single operating movement of the cam 27 and the lever 23. A relatively slow easy continuous motion of the transfer mechanism is thus obtained and the operating parts remain at rest except when called into action at the time of a shuttle transfer.

Having thus described my invention and the advantages thereof, I do not wish to be otherwise limited to the details herein disclosed, but what I claim is:—

1. In a shuttle changing loom, in combination, a shuttle removal box and means to give said box a single continuous upward movement to discharge position, and a succeeding continuous downward movement to normal receiving position after each shuttle transfer.

2. In a shuttle changing loom, in combination, a shuttle removal box and means to give said box a single continuous upward movement to discharge position, and a succeeding continuous downward movement to normal receiving position after each shuttle transfer, said movements occurring in unbroken sequence.

3. In a shuttle changing loom, in combination, a shuttle storage receptacle, a removal box and means to move said box toward and thereafter from said receptacle, said means comprising a cam, and means to give said cam a single continuous revolution after indication of transfer.

4. In a shuttle changing loom, in combination, a shuttle storage receptacle, a removal box and means to move said box toward and thereafter from said receptacle, said means comprising a cam, driving means to give said cam a continuous rotary movement, devices to connect said driving means to said cam after indication of transfer, and means to positively disconnect said cam after a single continuous revolution thereof.

5. In a shuttle changing loom, in combination, a shuttle removal box, a lever supporting said box, a link connected to said lever and having a cam roll, an actuating cam, and means to give said cam a single continuous revolution after indication of transfer, said cam having a depression adapted to receive said roll as the parts return to normal inoperative position.

6. In a shuttle changing loom, in combination, a shuttle removal box, a lever supporting said box, a link connected to said lever and having a cam roll, an actuating cam, and means to give said cam a single continuous revolution after indication of transfer, said cam being rotatably supported and the lower end of said link being guided in vertical movement by a slotted connection with the support of said cam.

7. In a shuttle changing loom, in combination, a shuttle storage receptacle, a re-

- moval box and means to move said box toward and from said receptacle, said means comprising a cam, a gear rotatable with said cam, a continuously driven shaft, a pinion loose on said shaft, means to clutch said pinion to said shaft, and a device on said gear effective to positively disengage said pinion from said shaft after a single revolution of said gear and cam.
8. In a shuttle changing loom, in combination, a shuttle storage receptacle, a removal box and means to move said box toward and from said receptacle, said means comprising a cam, a gear rotatable with said cam, a continuously driven shaft, a clutch, 15 a relatively light spring normally holding said clutch disengaged, a relatively heavy spring encircling said shaft and abutting said pinion, and means to compress said latter spring after indication of transfer to 20 yieldingly move said pinion to engage said clutch.
- In testimony whereof I have hereunto affixed my signature.

AUGUSTIN J. CHEVRETTE.
